UNITED STATES PATENT OFFICE.

JAMES W. DUSTIN, OF CONOWINGO, ASSIGNOR TO CHARLES C. CALDWELL,
OF LIBERTY GROVE, MARYLAND.

SAFETY DEVICE FOR ELEVATORS.

SPECIFICATION forming part of Letters Patent No. 393,425, dated November 27, 1888.

Application filed June 13, 1887. Serial No. 241,108. (No model.)

To all whom it may concern:

Be it known that I, JAMES W. DUSTIN, a citizen of the United States, residing at Conowingo, in the county of Cecil and State of Maryland, have invented certain new and useful Improvements in Safety Devices for Elevators; and I do hereby declare the following to be a full, clear, and exact description of the invention, such as will enable others skilled in the art to which it appertains to make and use the same.

My invention relates to a safety device for elevators to prevent them falling in case the hoisting-cable should break or suddenly slacken.

The object of the invention is to provide a simple and efficient device which will instantly lock the car at any point of its travel before said car and its load can have time to acquire a momentum. In most safety-clutches they are so arranged that the rack is directly engaged by the clutch, and the latter has to make considerable sweep before it can lock the car. The time lost in this action is sufficient to allow the car to drop the distance of one or more cogs before the clutch comes into active engagement with the rack. The momentum of the car acquired in this time when loaded is enormous, and the cogs are liable to be broken off or the clutch itself impaired. The importance, therefore, of instantaneously locking the car will be appreciated. In other forms where an idle-wheel gearing with a side rack is used the clutch is normally held so far from the idle-wheel that it consumes time in coming into engagement with said wheel when the moment of danger arrives.

My invention consists in mounting on the car a gear-wheel engaging a side rack and in providing a special form of locking arm for the gear-wheel, the novel features of which will be hereinafter fully described in the specification and definitely pointed out in the claims; also, in rendering the locking-arm adjustable in relation to the gear-wheel, so that it can be brought into a close relation to the cogs of the latter in any season and be rendered independent of changes due to temperature or constant usage.

In the accompanying drawings, which illustrate my invention as applied to a passenger

elevator-car, though of course it is applicable to any form of car that is raised and lowered from different horizontal levels, Figure 1 is a front elevation, with part broken away, so as to better illustrate the locking mechanism, of 55 an elevator-car provided with my improvements. Fig. 2 is a detached view of one side of the car, showing the locking devices on a larger scale.

The hoisting-cable P is connected by a suitable pin, C, to two pivoted levers, F F, in the car, hung on suitable bearings, E E. These levers are slotted at their inner ends, so as to permit them to spread sufficiently when the hoisting-cable yields through its being broken 65 or through a giving way of the elevating machinery. To suitable supports on the top of the car are attached springs bearing on the levers. The springs are normally compressed. I have shown a leaf-spring, M, and a spiral 70 spring, N, for each lever. Either would be sufficient if made of great resiliency; but by providing more than one an additional guard against accident is furnished. Each lever F carries an arm, G, (see Figs. 1 and 2,) provided with a screw-thread at its end, and a link, H, having threaded apertures in its ends, engages the end of arm G and a pivoted threaded rod, I, attached to a locking-arm, K. This locking arm is somewhat like a stirrup 80 pivoted to a bearing above a gear-wheel, D, and between the rack A and the inner extreme point of the gear-wheel. By pivoting the locking-arm at such a point a maximum efficiency when said arm is under tension is secured, since 85 the engaging-face of the locking-arm is not forced away from the cogs, as it would be if pivoted at a point outside of a vertical line cutting the wheel. Moreover, the strain on the arm itself is purely tensile, whereas there 90 would be a tendency to buckle if the pivotal point were outside of the specified vertical. The gear wheels D D are secured in bearings on each side of the car, and engage the vertical racks A A, secured to the guide-bars B B of the 95 car. By turning the take-up links H H a delicate adjustment of the locking-arms K K with reference to the wheels D D can be made. The two arms of each locking-arm K K lie partly over the gear-wheel, and the transverse por- 100

tion or web at the free end of each is normally adjusted so as to just clear the gear-wheels. These locking-arms are made of wrought-steel or other metal having great tensile strength, and the face which engages the cogs of the gear-wheels when the locking-arm is in action is given an inclination such that it will lie parallel with the beveled tip of the cogs of the gear-wheel in order that the slightest depression of the locking-arm will cause a firm lock of the gear-wheel.

The operation of the locking arm will now be understood. The clutching-webs of the locking arms or stirrups K K are adjusted by turning the links H H until the webs just clear the cogs of the gear-wheels. A check-block, Q, secured to the top of the elevator, prevents the locking-arm being pulled far from the cogs of said gear-wheel when great weight is being carried, and also prevents straining of the springs M N. If, now, the hoisting-cable should break or give way, the springs would be free to act, and by reason of the close adjustment of the locking-arms the cogs of the wheels D D are instantly engaged. I have found in practice that a movement of one-sixteenth of an inch is sufficient to cause a firm engagement of the locking-arm, and have repeatedly released a car carrying two thousand pounds, the elevator not sinking more than one-fourth of an inch. It will be seen, therefore, that this sudden arrest insures safety to all the parts. I have shown the car provided with a locking-arm for each rack. While I prefer this structure, a single locking-arm might serve the desired purpose.

Having thus fully described my invention, what I claim, and desire to secure by Letters Patent, is—

1. The combination of an elevator-car, aside rack parallel to the line of travel of the car, a gear-wheel mounted upon the car in operative relation to the rack, an adjustable locking-arm

carried by the car and adapted to lock the gear-wheel, but normally out of engagement therewith, and means for shifting said arm into engagement with the gear-wheel when the car is released from its hoisting devices.

2. The combination of an elevator-car, side racks parallel to the line of travel of the car, wheels carried by the car gearing with said racks, an adjustable locking-arm for each wheel normally lying tangential to the wheel, connections between each locking arm and a hoisting-cable, whereby it is normally held out of engagement with its wheel, and means for giving it a radial thrust toward the wheel, so as to engage the same when the cable suddenly yields.

3. The combination of an elevator-car, side racks parallel to the line of travel of the car, wheels carried by the car gearing with said rack, a safety locking-arm for each wheel pivoted on a vertical line cutting the wheel, the engaging-face of the locking-arm being inclined with relation to the cogs, so as to firmly engage the top of the cog when brought into action, connections between each locking-arm and a hoisting-cable, whereby the locking-arm is held normally out of engagement with the wheel, and springs for throwing it into engagement when the cable suddenly yields.

4. The combination of an elevator-car, side racks parallel to the line of travel of the car, gear-wheels D D, secured to the car, engaging the racks, adjustable locking-arms K K, having engaging-webs, levers F F, springs engaged by said levers, a hoisting-cable connected to said levers, and a check above the levers to prevent undue strain on the springs.

In testimony whereof I affix my signature in presence of two witnesses.

JAMES W. DUSTIN.
